UNITED STATES PATENT OFFICE.

GUSTAV STROM, OF PONTIAC, MICHIGAN, ASSIGNOR OF THIRTY ONE-HUNDREDTHS
TO PETER D. JOHNSTON, OF PONTIAC, MICHIGAN.

RAILWAY TIE.

Application filed July 3, 1922. Serial No. 572,695.

To all whom it may concern:

Be it known that I, GUSTAV STROM, a citizen of the United States of America, residing at Pontiac, in the county of Oakland and State of Michigan, have invented certain new and useful Improvements in Railway Ties, of which the following is a specification, reference being had therein to the accompanying drawings:

- 10 The invention relates to railway ties employing in their construction reinforced concrete and it is the object of the present invention to obtain a construction provided with rail securing means, which permits of quickly engaging and clamping the rail to the tie. A further feature of the construction is the means by which the rail may be readily detached when this is desired, and with these objects in view the invention consists in the construction as hereinafter set forth.

In the drawings:

Figure 1 is a plan view of a portion of the tie showing the rail securing means;

25 Figure 2 is a central longitudinal section through Figure 1;

Figure 3 is a transverse section;

Figure 4 is an end elevation.

In the construction of concrete railway ties it is usual to form of the concrete end sections which are arranged below the respective rails, and to connect such sections by a metallic tie member embedded therein. With my improvement the tie member, in addition to its function of connecting the two concrete ends, also forms a reinforcement for said ends and an anchor for the rail-securing means. In detail, A is one of the concrete end sections, preferably provided with an enlarged base B and inwardly sloping sides C to form a top of reduced area. D is the metallic connecting member which is in the form of a bar centrally embedded in the section A below the top face thereof. The bar D is further provided with spaced upwardly extending lugs E and E', which at their upper ends are rounded at F to form a pivot or fulcrum for the rail-securing clamps. These clamps G have inwardly extending portions H for bearing upon the flange of the rail and downwardly extending portions I which are pivotally connected to inwardly extending links J. The inner ends of the links J are spaced from each other and, in the locked position

of the rail, engage opposite sides of a wedge or key member K. However, the links J are initially raised above the key member, as shown in dotted lines, which permits the member G to swing about the fulcrum bearing F and into a position where the lugs H will clear the base flange L of the rail M.

On opposite sides of the member D are placed the supporting blocks N and M' preferably of wood, which blocks engage recesses in the upper face of the concrete member A. O is a bolt secured to the key member L and slidably engaging a transverse recess in the member D, said bolt extending to the opposite sides of the blocks N and N' and forming a means for securing end clamping plates P and P'. There is left, however, an open channel between the adjacent inner edges of the blocks N and N' for receiving the links J and permitting the movement thereof.

With the construction as thus far described, when the tie is first placed in position, the links J are in the position shown in dotted lines, which permits the members G to be swung outward, as also indicated by dotted lines. In this position the base L of the rail M may be placed between the members G so as to rest upon the blocks N and N'. The members G are then swung upon their fulcrum bearings F, in doing which the links J are drawn outward until their inner ends drop off from the wedge or key K and, in falling, engage the inclined sides of said wedge so as to be locked from return movement. Therefore, the lugs or fingers H on the members G will clamp downward upon the flange L of the rail and will hold the latter from displacement. If at any time it is desired to disengage the rail, the bolt O is moved longitudinally so as to withdraw the wedge K from between the inner ends of the links J. This movement is permitted by first loosening the ends Q by which the clamping plates P are secured to the bolt, after which the bolt may be moved to carry with it the wedge K to engage a laterally extending recess R. When the wedge K is removed from the ends of the links J, the members G can again be swung upon the fulcrum pivots F, which permits of disengaging the rail.

The links J may be pivotally attached to the members G in any suitable manner, but, as shown, they are connected by a tie wire S which is sufficiently flexible to permit the

swinging of the links while retaining the same permanently attached to the members G. The wedge K has its opposite sides inclined at such an angle that when the ends 5 of the links J are moved outward, they will drop into engagement with these inclined sides and will wedge to firmly clamp the member H upon the rail.

What I claim as my invention is:

- 10 1. In a railway tie, the combination with a concrete body forming a rail support, of a metallic member embedded in said body, rail clamps pivotally secured to said embedded member to be movable thereon into and out of clamping position, and means for locking said clamps in their clamped position.
- 20 2. In a railway tie, the combination with spaced concrete members forming rail supports, of a metallic member constituting a tie between said concrete members and having portions embedded therein, and rail clamps pivotally engaging the embedded portions of said member to be movable into and out of clamping engagement with the rail.
- 30 3. In a railway tie, the combination with a concrete member forming a rail support, of a metallic member embedded therein having upwardly extending lugs forming rounded fulcrum bearings, rail clamps engaging said fulcrum bearings, links secured to said clamps and projecting inward therefrom, and a wedge member with which said 35 links automatically engage on the swinging of the same on their fulcrum bearings.
- 40 4. In a railway tie, the combination with a concrete member forming a rail support, of a metallic member embedded therein having upwardly extending lugs forming rounded fulcrum bearings, rail clamps engaging said fulcrum bearings, links pivotally secured to said clamps and extending inward therefrom, blocks on opposite sides 45 of said links forming a cushion support for the rail and a removable member passing transversely through said blocks in a posi-

tion to engage the ends of said links when said clamps are engaged with the rail flange and to thereby lock said clamps from disengagement. 50

5. In a railway tie, the combination with a concrete member forming a rail support, of a metallic member embedded therein having upwardly extending lugs forming 55 rounded fulcrum bearings, rail clamps pivotally engaging said rounded fulcrum bearings links pivotally secured to the lower ends of said rail clamps and projecting inward therefrom, blocks upon opposite sides of said links forming a cushion support for the base of the rail with a channel between the same in which said links can move vertically and longitudinally, a removable member extending transversely of said blocks over which 60 said links extend when said clamps are in open position to receive the rail, said transverse member engaging the ends of said links to lock the same when said clamps are turned down to secure the rail. 65

6. In a railway tie, the combination with a concrete member forming a rail support, of a metallic member embedded therein having upwardly extending lugs forming 70 rounded fulcrum bearings, rail clamps pivotally engaging said rounded fulcrum bearings, links pivotally secured to said clamps and projecting inward therefrom, wooden blocks on opposite sides of said links forming a cushion support for the base of the 75 rail, said blocks forming therebetween a channel in which said links are vertically and longitudinally adjustable, clamping plates on opposite sides of said blocks, an adjustable member extending transversely 80 through said clamping plates and blocks and having a wedge-shaped central portion over which said links extend in the open position of said clamps, said wedge-shaped portion forming an abutment for the ends of said 85 links when said clamps are turned down into locking engagement with the rail. 90

In testimony whereof I affix my signature.

GUSTAV STROM.
